W. H. PHILLIPS

CONDENSING SYSTEM

Filed Feb. 19, 1921

By his Attorneys
Philip Sawyer & Co. Kennedy

UNITED STATES PATENT OFFICE.

WILL H. PHILLIPS, OF CHICAGO, ILLINOIS, ASSIGNOR TO WORTHINGTON PUMP AND MACHINERY CORPORATION, OF NEW YORK, N. Y., A CORPORATION OF VIRGINIA.

CONDENSING SYSTEM.

Application filed February 19, 1921. Serial No. 446,382.

To all whom it may concern:

Be it known that I, WILL H. PHILLIPS, a citizen of the United States, residing at Chicago, county of Cook, and State of Illinois, have invented certain new and useful Improvements in Condensing Systems, fully described and represented in the following specification and the accompanying drawings, forming a part of the same.

10 The present invention relates to an improved apparatus for the control of condensing steam engine systems.

In operating a condensing steam engine it is necessary to remove the air from the condenser. If the engine, condenser and connections are air tight, the air to be removed from the condenser is only that which, accompanying the steam from the boiler, passes through the engine with the steam 20 and escapes from the water of condensation in the condenser. I have found that under normal operating conditions the average amount of such air entering the condenser is about proportional to the amount of steam used. Hence by continuously metering the air as it is discharged from the condenser it is possible to determine the operating condition of the system. So long as the amount of air discharged from the condenser is approximately normal, the condition of the engine, condenser, connections, and pump 30 may be considered as normal; but any increase above the normal of the air discharge from the condenser, is an indication that a leak has developed in the system, or some other abnormal condition has arisen.

It is very important that the engineer in charge of the system should have immediate notice of such abnormal condition and it is 40 the purpose of my present invention to provide means whereby such notice will be given promptly.

With this object in view, my invention comprises the addition to a condensing steam engine system of means for removing the air from the condenser and discharging it, and continuously acting means for determining the rate of discharge of the air.

The means for removing the air from the condenser may be of various types but preferably comprises that type of air pump called a hydraulic pump or liquid thrower, one example of which type is disclosed in U. S. Letters Patent 1,031,143 to Mueller, 50 dated July 2, 1912, and the invention will

be illustrated as applied in connection with such a pump.

The invention will first be described in connection with the accompanying drawings and then more particularly pointed out in 60 the claims.

In the drawings,—

Figure 1 is a diagrammatic view partly in section of an apparatus embodying the invention;

Figure 2 is a detail section on a larger scale of the dome portion of the sealing tank; and

Figure 3 is a plan view of the dome.

Referring to Fig. 1 of the drawings, A represents a surface condenser having a hot well B from which the water of condensation is removed through pipe 1 by any suitable means, as, for example, the centrifugal discharge pump C. The air and uncondensed vapor are drawn off through pipe 2 by suitable air removing mechanism. As illustrated in the drawings, the air-removing mechanism is a hydraulic air discharge pump or compressor D, such as is fully shown and described in the United States Letters Patent to Mueller hereinbefore mentioned. The pump D is arranged to receive liquid supplied through pipe 3 from a centrifugal circulating pump E, and discharges its liquid and compressed air through a discharge nozzle 4 into a tank F from which the circulating pump E takes its liquid supply through a pipe 5 connected to the tank near its bottom. The tank F is provided with suitable means for maintaining an air-space above the liquid level in the tank. In the form of the apparatus shown in Fig. 1 this may be accomplished by providing a draw off pipe 6, having a cock 7, controlled 80 by a float 8. The pipe 6 extends downward inside the tank, as shown. A water gauge 6' may also be provided.

The tank is supposed to be supplied initially with water to a level above the lower end of the discharge nozzle 4. The liquid level initially provided would remain constant if no additional liquid entered the tank, but because the pump D withdraws vapor as well as air from the condenser, this vapor will be condensed in the tank F and tend to raise the water level. The float valve serves to prevent this change of water level and this insures a constant air space in the tank F above its water level and a con- 110

stant head of water on the end of the discharge nozzle 4. The tank F may also be provided with an inlet pipe 9 for make-up water, which pipe is provided with a manually operable valve 9', and a water sealed overflow pipe 30 permits the large escape of air discharged in starting.

The tank is provided with means for continuously discharging the air from the space 10 above the water level and for continuously determining the rate of discharge of such air.

While various devices for making this determination may be employed, such as, 15 for example, an ordinary flow meter, in the preferred embodiment of the invention shown, an orifice meter is used, and the tank F is provided with a dome G on top of the tank and open to the air space thereof. The 20 cap g of the dome has a circular raised portion indicated at 10 at the center of which is fixed an upwardly extending stud 11 screw-threaded at its upper end. On this stud is journaled a rotatable orifice-plate H having 25 a series of orifices of different areas.

In Fig. 3 of the drawings these orifices 12 are shown as circular and arranged in a series gradually increasing from the smallest orifice to the largest, the centers of the orifices lying on the circumference of a circle whose center is the axis of the stud 11.

The orifice plate H is arranged to be forced against the cap g of the dome by any suitable means. In the embodiment shown, 35 the upper end of the stud 11 is provided with a nut 13, conveniently provided with a handle 14, and between the nut and the orifice plate H is placed a helical compression spring 15, surrounding the stud 11. In 40 order to make an air-tight joint between the orifice plate and the cap g, a suitable gasket 16 may be provided if desired, this being secured to the cap of the dome.

The cap g is provided with a single orifice 45 indicated at 17, Fig. 2, whose area is not less, and advantageously somewhat greater than that of the largest orifice in the orifice plate, the center of this orifice 17 being so located that the center of any desired orifice 50 of the orifice plate may be brought into alignment with the orifice 17 by rotating the orifice plate H. The gasket 16, of course, has a similar hole in register with the orifice 17.

55 The dome G is provided with suitable means for indicating the pressure and temperature of the air within the dome.

In the drawings, the means for indicating the pressure comprises an ordinary manometer, indicated at I. The liquid of this manometer may be colored water. Its scale 60 18, which is adjustable as usual, will be suitably graduated to indicate the pressure of the air. The means for indicating the temperature comprises the usual mercury ther-

70 mometer, as indicated at K, its inner end projecting well into the dome in order to show as accurately as possible the temperature of the air. This thermometer is provided with the usual graduations.

It will be noted that the air from the tank F can escape only through that orifice in the orifice plate which is at such time in alignment with the hole in the cap g of the dome. Even the largest orifice of the orifice 75 plates allows only a throttled discharge of the air from the tank, so that in regular operation there will be some pressure, though perhaps only a slight one, in the dome. The amount of this pressure may be regulated by 80 rotating the orifice plate H to bring any desired orifice into operation.

By reading the pressure from the manometer scale and the temperature from the thermometer scale, the operator may at once 85 determine the rate of discharge of air from the tank F. In order that he may not be compelled to rely on his memory, a suitable table may be provided for reference in which 90 table the rate of discharge may be shown for temperatures and pressures which will ordinarily occur in practice, and for each orifice of the orifice plate H.

In order to reduce or eliminate the temperature variable, the water in the tank may 95 be maintained at as nearly a constant temperature as is possible in practice. This may be done by letting in make-up water from time to time, or if desired by allowing a slight constant flow of make-up water into 100 the tank, the float valve serving to maintain the water level, by permitting a constant discharge corresponding to the inflow of make-up water.

When desired the tank F may be provided 105 with special cooling coils. In the example shown in Fig. 1 the tank F is provided with a plurality of cooling tubes indicated at 19 and with baffle plates 20 arranged to cause 110 a suitable convoluted flow of the water through the tank F thus forcing it to pass in contact with the cooling tubes. These tubes may conduct cooling water from any source. In the usual condenser systems the cooling tubes may be arranged in parallel 115 with the first-pass tubes of the main condenser.

It will be apparent that with any given plant or system, the temperature variations 120 can be kept within reasonable limits for any given season of the year, and that by practice the operator will remember the normal pressure readings, so that he will immediately notice any unusual variations of pressure, thus detecting quickly a change of operating 125 conditions due to leakage in the system. The orifices of the orifice plate are given differing convenient areas so that the pressure within the tanks may be kept within a certain range. The pressure and temperature 130

readings, as well as the orifice in use, may be indicated and recorded at the engine gauge board by any suitable means, if the location of the engine relatively to the condenser is such as to make this desirable, which usually will be the case in large systems.

What is claimed is:

1. The combination, with a condenser, and means for continuously removing and discharging the air from the condenser, of continuously acting means for determining the rate of discharge of the air.
2. The combination, with a condenser, and means for discharging the water of condensation therefrom, of means for separately and continuously removing and discharging the air from the condenser separately from the water of condensation, and continuously acting means for determining the rate of discharge of the air.
3. The combination, with a condenser, of means for removing air and vapors from the condenser, means for continuously condensing the vapors and discharging the air, and continuously acting means for determining the rate of discharge of such air.
4. The combination, with a condenser and a tank having an air discharge outlet ar-

ranged to throttle the air discharge and thereby maintain an air pressure in the tank, of means for discharging the air from the condenser into said tank, and means for determining the temperature and pressure of the air in the tank.

30

5. The combination, with a condenser, of a tank having an air discharge outlet, a hydraulic air pump arranged to discharge air from the condenser to the tank, means for circulating water from the tank to the pump, an air-pressure indicator and a thermometer connected to the tank, and means for varying the size of the air-discharge outlet of the tank in predetermined steps.

35

6. The combination, with a condenser, of a tank having an air discharge outlet, a hydraulic air pump arranged to discharge air from the condenser to the tank, means for circulating water from the tank to the pump, an air-pressure indicator and a thermometer connected to the tank, means for varying the size of the air-discharge outlet of the tank in predetermined steps, and means for cooling the water in the tank.

40

In testimony whereof, I have hereunto set my hand.

45

WILL H. PHILLIPS.
